US00D518837S

(12) **United States Design Patent** (10) **Patent No.:** **US D518,837 S**
(45) **Date of Patent:** **** Apr. 11, 2006**

(54) **ACTUATOR**

(75) Inventor: **Kenji Taguchi**, Yokohama (JP)

(73) Assignee: **Jidosha Denki Kogyo Co., Ltd.**,
Yokohama (JP)

(**) Term: **14 Years**

(21) Appl. No.: **29/201,490**

(22) Filed: **Mar. 17, 2004**

(30) **Foreign Application Priority Data**

Sep. 17, 2003 (JP) 2003-031243

(51) **LOC (8) Cl. 15-09**

(52) **U.S. Cl. D15/143**

(58) **Field of Classification Search** D15/143;
74/149, 331, 339, 340, 343, 402, 409, 411.5,
74/425; 192/144, 223, 223.2, 223.3; 310/77,
310/83, 89, 239

See application file for complete search history.
